DESIGN FOR A COAL-STOVE.

SPECIFICATION forming part of Design No. 13,917, dated May 22, 1883.
Application filed April 23, 1883. Term of patent 7 years.

UNITED STATES PATENT OFFICE.

H. CLAY BASCOM AND CYRUS A. HODGES, OF TROY, AND TOBIAS S. HEISTER, OF LANSINGBURG, ASSIGNORS TO THE N. S. VEDDER PATTERN WORKS, BASCOM, GALBRAITH & CO., OF TROY, NEW YORK.

DESIGN FOR A COAL-STOVE.

SPECIFICATION forming part of Design No. 13,917, dated May 22, 1883.

Application filed April 23, 1883. Term of patent 7 years.

To all whom it may concern:

Be it known that we, H. CLAY BASCOM and CYRUS A. HODGES, citizens of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for Coal-Stoves, of which the following is a specification, reference being had to the accompanying cut, print, or engraving, illustrating said new design.

The design for the vase A consists of a body composed of the semi-globular lower portion, *a*, and higher concavely-curved part, *b*, in combination with a crest-plate composed of the top part, *c*, lower side parts, *d*, and intervening portions, *e*, all shaped, ornamented, and arranged together so as to present substantially the same appearance as is represented in the aforesaid print.

The design for the panels B consists of the compound ornament C and panel-border D, all shaped and arranged together so as to present substantially the same appearance as is illustrated in the aforesaid engraving.

The design for the ornament C consists of the two curved moldings *f*, united in opposite angles, and the oblique band *g*, and the fruit-and-leaf branch *h*, all shaped and disposed within said moldings substantially as shown in the aforesaid cut.

The design for the combustion-chamber section E consists of the mica-light door F and panel portions G, shaped, ornamented, and arranged so as to appear substantially the same as illustrated in the aforesaid print.

The design for the fire-pot section H consists of the open-work upper and lower parts, I and J, each composed of special ornamental figures and forms, and arranged together so as to present substantially the same appearance as is represented in the aforesaid engraving.

The design for the base-section K consists of the quadrilateral bottom plate, L, having rounded corners *i* and the series of angle or-

naments *j*, in connection with the ash-pit portion M, having the form of a frustum of a four-sided pyramid, with recessed rounded corners *k* and the series of ornamentations *l* and *m*, all shaped and arranged substantially as shown in the aforesaid print.

The design for the legs consists of the compound ornament N, having the three round-ended bars *n*, with top and bottom ornaments, *o p*, on a swelled surface, *q*, having an ornamental edging, *r*, all shaped and arranged together substantially as shown in the aforesaid cut.

What we claim as our joint invention is—

1. The design for the vase A, composed of the parts *a b* and *c d e*, shaped and arranged together as described.

2. The design for the panels B, composed of the compound inner ornament, C, and ornamental border D, composed and arranged together as set forth.

3. The design for the ornament C, consisting of the curved border-moldings *f* and inner parts, *g h*, shaped and arranged as described.

4. The design for the combustion-chamber section E, composed of the parts F and G, shaped, ornamented, and arranged together as set forth.

5. The design for the section H, consisting of the two open-work ornamental parts, I and J, composed, shaped, and arranged together as set forth.

6. The design for the section K, composed of the parts L *i j* and M *k l m*, shaped and arranged as described.

7. The design for the legs, consisting of the parts N *n o p* and *q r*, shaped and disposed as set forth.

In testimony whereof we hereunto set our hands, in the presence of two subscribing witnesses, this 20th day of April, 1883.

H. CLAY BASCOM,
CYRUS A. HODGES,
TOBIAS S. HEISTER.

Witnesses:

AUSTIN F. PARK,
ASAHEL D. LYON.
